W. J. MacKENZIE

APPARATUS FOR MAKING CONCRETE POSTS

Filed August 16, 1924

Inventor:
Wm. J. MacKenzie,
By his Attorney,
Horace Barnes.

UNITED STATES PATENT OFFICE.

WILLIAM J. MACKENZIE, OF PORTLAND, OREGON.

APPARATUS FOR MAKING CONCRETE POSTS.

Application filed August 16, 1924. Serial No. 732,375.

This invention relates to improvements in apparatus for making concrete posts.

The object of my invention is to provide a sectional mold of simple construction 5 wherein posts of cementitious composition and analogous structures may be formed while in vertical and in reversed position to that which they will assume when positioned in actual use whereby the exposed end and 10 sides of the post when removed from the mold will be in practically finished condition.

A further object of the invention resides in the provision of novel devices and means 15 for quickly assembling and separating the mold parts so that a considerable saving in time is effected over operations now in common use and whereby the mold can be readily removed or taken apart without injury 20 to the newly formed post.

Other objects and advantages and objects 25 relating to parts, combinations and arrangements of the invention such as the devices for forming the finished end of the post and devices for supporting the reinforcement 30 material will hereinafter appear in the detailed description to follow.

The invention is illustrated by way of example in the accompanying drawings, in 35 which:

Figure 1 is a view in side elevation, partly broken away, of an improved mold for concrete posts embodying my invention.

Fig. 2 is a top plan view of the same.

Fig. 3 is a view in cross-section on line 35 3—3 of Fig. 1.

Fig. 4 is a top plan view of the base-plate of the invention, shown detached.

Fig. 5 is a view in vertical cross-section 40 of Fig. 4.

Fig. 6 is a view partly in side elevation and partly in vertical section of a post formed in accordance with my invention set in the earth in operation condition.

45 Referring to said views, wherein similar reference characters indicate similar parts in the several views, and particularly to Fig. 6, the reference numeral 1 indicates the upper exposed portion of a post of concrete material formed in the mold hereinafter

more particularly described, and 2 the reinforcing metal rods arranged symmetrically adjacent the corners thereof. Said rods extend downwardly in parallel relation be-

yond the post-portion 1, as at 2', and are 55 set into a column 3 of concrete material formed in an excavation in the ground 4.

Said post is formed with relatively rectangular side faces 5 having the corners thereof chamfered, as at 6, and its upper 60 extremity 7 is likewise formed with peripheral edges chamfered inwardly from the faces 5 and corners 6, as at 8.

A vertical hole is formed in the ground in which the post is to be set having a diameter several inches larger than the diameter of the post, which hole is filled with plastic concrete including a relatively considerable proportion of large gravel to form said column 3 and the protruding ends 2' 70 of the reinforcing rods 2 are thrust into the fresh concrete with the lower end 10 of the post extending slightly into said concrete.

The concrete material is thereupon allowed to set and forms a rigid monolithic structure with the post about which the surrounding earth has not been moved and which affords a strong and durable support for the rails 11 of a fence or barrier 75 guarding a gulch or declivity by the side of a road. Said posts are formed in the mold with spaced groups of holes through which the bolts 12 extend by which the rails 11 are securely fixed to the posts.

Said post-portion 1 is formed in a mold, 85 illustrated in Figs. 1 to 5 of the drawings, and which consists in two substantially similar wall-sections 15 and 16, and a base-plate 17. Each said wall-section is made of cast iron or steel and has its interior surface 90 coming in contact with and adapted to form the surface of the post ground and polished. Each said section includes two walls 18 corresponding to the faces 5 of the post disposed relatively at ninety degrees with an intermediate chamfer-portion 20 and at one side joining the outer edge of one of said walls 18 a further chamfer-portion 21. With the two sections connected together with said portions 21 disposed upon opposite sides a mold 95 100 will be provided to form a post with side walls of the configuration described.

The plate 17 is formed with a circular base 22 having an integral and continuous raised bead 23 formed symmetrically thereon in the 105 configuration of the cross-section of said wall mold and having portions 25 inclined inwardly therefrom and a horizontally plane

central portion 26 to form the chamfer-portions 8 and the top 7 of said post, respectively.

Said sections 15 and 16 are each formed with upper and lower peripheral flanges 27 and 28, respectively, the lower said flanges fitting snugly upon said bead 23 with inner edges aligned therewith whereby the base-plate serves to mold the top of the post. Said lower flanges 28 are each formed with a slot 30 intermediate its lateral, vertical edges into which a shackle-bolt 31 pivoted to the base-plate engages and serves to clamp the wall-sections to the base-plate by means of a wing-nut 32.

At the lateral edges of said wall-sections they are formed with vertical flanges 33 which are provided with slots 35 at spaced intervals on each side. Shackle-bolts 36 are connected at each side to one of said sections at said slots and serve to couple the sections together by means of wing-nuts 37 in a well understood manner.

Said base-plate is provided with integral bosses 40 and 41 intermediate the shackle-bolts 31 into which dowel-pins 42 and 43 are respectively positioned to engage in holes in the flange 28 of said wall-section 16, that is to say, said dowel-pins are both located upon the same side of a line drawn through the joint between said wall-sections so that both pins will engage in the same wall-section. Other dowel-pins 45 protrude from the face of the flanges 33 of the wall-section 16 engaging in corresponding holes in the opposing flanges of section 15 whereby the sections are fitted together with exactness.

Each of said wall-sections is formed with groups of holes 46 in one of their walls 18 and upon relatively opposite walls to receive tapered steel pins 47 which extend across the mold space and protrude at either side. Said pins 47 are desirably case-hardened at their smaller end so that they may be hammered thereupon to remove them from the mold after the post is formed without danger of battering their ends.

Brackets 48 are detachably mounted upon the upper flange 27 by screw-bolts 50 and each include a vertically disposed integral sleeve 51 having a square aperture or of other configuration suitable to the reinforcing rods employed and through which a set-screw is provided.

Reinforcement rods 2 are secured in said apertures of the brackets and are secured by said set-screws so that their end 2" is spaced upwardly from the base-plate for about an inch. Said brackets are secured at each of the four corners of the mold so that said rods are extended into the mold adjacent the corners of the post, that is to say adjacent the chamfered portions 6 thereof.

Trunnions 53 are rigidly secured to the respective wall-sections extending at oppo-

site corners of the mold when assembled whereby the mold and contained post may be conveyed where desired by a suitable truck.

With the mold-parts as described internally lubricated and assembled in the manner set forth and the rods 2 placed in position and clamped within the brackets 48, and the pins 47 inserted as described, the mold is filled with plastic concrete material and jarred on a jogging-platform (not shown), or the material may be tamped in any suitable manner to increase the density of the completed post. As the material in the mold settles down fresh material is shoveled in the top until the mold will hold no more whereupon the material is leveled off on the plane of the upper flange 27.

When the mold has been filled and sufficiently tamped the brackets 48 are loosened both from the mold-sections and from the rods and slipped upwardly over and removed from the rods. The filled mold may then be removed to a suitable place to set and in a few hours the wall-sections may be removed by wedging them apart, the section 15 coming away from the contained post laterally and then the section 16 is lifted from the bottom to free it from the dowel-pins 42 and 43. The post now stands upon its end 7 in the base-plate and remains in this position for another period after which it is readily removed from the base-plate and the pins 47 may then be knocked out leaving transverse holes in their places.

The fact that the posts are formed vertically and in reversed position, that is to say, with their normally upper end at the bottom of the mold, and that all of the exposed portions of the post are formed against a polished metal surface results in the production of a post having a smooth finished surface on all of its exposed portions and will require but little or no subsequent treatment to produce a post of finished and highly pleasing appearance. The post is usually painted with a thin neat cement mixture to give a surface of fine texture.

A substantially square post having no rectangular corners, either on its vertical sides or about its top affords a post not only pleasing in appearance but particularly safeguarded against chipping and cracks at such corners, especially in view of the metal rod reinforcement positioned adjacent such vertical corners.

Having described my invention, what I claim, is:

1. A mold for concrete posts, consisting in a metal base-plate having an integral, raised bead providing a depression within said plate for forming the post-end, a pair of wall-sections arranged to be supported on said bead, and screw-devices to clamp said

wall-sections in operative position on said bead.

2. A mold for concrete posts, consisting in a base-plate having an integral bead formed thereon to provide a depression within the plate to form the upper end of the post, and a pair of wall-sections mounted upon said bead with their inner surfaces flush with the inner edges of said bead, said wall-sections being detachably secured to said plate and to each other.

3. A mold for concrete posts, consisting in a pair of vertical wall-sections having opposing flanges at their vertical edges and horizontally disposed flanges at their lower edges, means to detachably secure said

sections together at their opposing flanges, a base-plate having an integral, continuous bead to support said lower flanges of the wall-sections, and means to detachably secure said wall-sections to the base.

4. A mold for concrete posts, consisting in a pair of wall-sections having horizontally disposed flanges at their upper and lower edges, a base upon which said wall-sections are secured, brackets secured upon said upper horizontal flanges, each said bracket being formed with a vertically disposed sleeve, each sleeve having a set-screw in its side wall to secure a reinforcement rod in suspended relation within the form.

WILLIAM J. MACKENZIE.
